UNITED STATES PATENT OFFICE

JOSEPH E. WAINWRIGHT, OF BROOKLYN, NEW YORK

VALVE SPRING COMPRESSOR

Application filed May 29, 1930. Serial No. 457,321.

This invention appertains to valve spring compressors and has for its object the production of a simple and efficient tool which will facilitate the compression of valve springs and at the same time efficiently hold the springs while the same are being compressed or are being released from the holding clips so as to prevent the springs from accidentally flying from the tool.

Another object of this invention is the production of a simple and efficient valve spring compression tool, the parts of which are made from standard or stock material and wherein the various parts will not require the use of an elaborate machine to manufacture and assemble the same.

A still further object of this invention is the production of a valve spring compressor, which is very sturdy in its construction, 20 simple in operation and which consists of a minimum number of parts.

Other objects and advantages of the present invention will appear throughout the following specification and claims.

In the drawings:

Figure 1 is a side elevation of the improved valve spring compressor.

Figure 2 is a vertical section therethrough.

Figure 3 is a top plan view thereof.

Figure 4 is a section taken on the line 4-4 of Figure 3.

Figure 5 is a section taken on the line 5-5 of Figure 3.

Figure 6 is a bottom plan view of the valve spring compressor partly broken away and certain parts broken away to show the structure thereof.

Figure 7 is a detail perspective view of the removable abutment plate which may be used in conjunction with the compressor.

By referring to the drawings it will be seen that 1 designates a support of any suitable or desired structure and this support may be of a rectangular block-like structure as shown in the drawings. A plurality of angular supporting brackets 2 are carried by the base or support 1 as indicated clearly in the drawings and these angle brackets support the parallel track rails 3, which rails 3

are held in spaced relation by means of suitable sleeves 4 fitting over the bolts 5. These brackets 2 are provided with inwardly extending overhanging bifurcated ends 6, which bifurcated ends overhang the upper edges of the trackways or track rails 3 to firmly hold the same in engagement with the supporting brackets 2.

An abutment shoe 7 is adjustably mounted upon the parallel track rails 3 and this abutment shoe 7 comprises an upper inverted U-shaped plate 8 and a lower substantially U-shaped plate 9, these plates 8 and 9 fitting over the respective upper and lower edges of the track rails 3 as shown clearly in Figure 4 of the drawings. The upper and lower plates 8 and 9 are held firmly in friction gripping engagement with the rails 3 by means of a locking bolt 10, the lower threaded end of which carries locking washers 11 and a wing nut 12. A wrench or locking lever 13 fits over the lower end of the bolt 10 and is provided with a downwardly bent bifurcated end 14 for fitting over one wing of the nut 12, thereby facilitating the locking and clamping of the abutment shoe 7 firmly upon the track rails 3. By means of the locking lever 13 it will be seen that a good leverage will be produced upon the nut 12, thereby permitting the same to be firmly bound in conjunction with the washers 11 against the lower plate 9 of the shoe 7. In this way the upper and lower plates 8 and 9 will be firmly drawn together in frictional contact with the upper and lower edges of the track rails 3. This shoe 7 is provided with an upwardly bent spring contacting finger 15 which is reinforced by means of a substantially L shaped bracing plate 16 which extends under the upper plate 8 of the shoe 7 and is secured thereto by means of a suitable rivet 17.

As shown in the drawings the compressor also comprises a compression shoe 18 which is slidably mounted upon the track rails 3 and this shoe 18 is similarly constructed to the shoe 7, the upper and lower plates thereof being connected by means of the bolt 19 upon which is mounted the lock nut 20, this bolt 19 constituting a pivot for the compres-

sion lever 21 shown clearly in Figure 3. The inner end of the compression lever 21 is connected by a pair of parallel links 22, which links are in turn pivotally connected as at 23 to the laterally extending end 24 of the supporting strap 25. This strap 25 passes down under the rails 3 and is provided with an upwardly turned end 26. A suitable bolt 27 constituting a centrally located transverse 5 bracing member passes therethrough and also passes through the rails 3 and carries a sleeve 28 which spaces the upstanding portion 29 of the strap 25 from the rails 3. It is to be understood that this tool may be used 10 in any suitable or desired manner and placed in any suitable or desired position to suit the convenience of the operator. It has been found convenient to place the tool against the chest of the operator in compressing a 15 spring so that the lever 21 may be pulled toward the operator in the compression of the spring thereby permitting the device to be very quickly and conveniently operated. It 20 of course should be understood that the device may be mounted in any suitable or desired manner upon a bench or other suitable and convenient work place.

It is further desired to point out that this compressor may be used for the purpose of 25 compressing valve springs of any particular type and may be used in conjunction with any suitable valve spring clips. However, for the purpose of using the device in conjunction with the particular clip which is 30 described in my previous Patent #1,614,218, issued January 11, 1927, wherein a holder is disclosed having spring engaging arms for progressively engaging the convolutions of the coil spring, a special abutment plate is 35 produced. This abutment plate is specifically illustrated in Figure 7 and comprises a disc-like abutment end 30 terminating in a laterally projecting tongue or shank 31 which is bifurcated as at 32 at its outer end to permit the bolt 19 on the compression shoe 18 to 40 readily slide therethrough as the shoe 18 is drawn down toward the abutment shoe 7. The ends of the bifurcated portion 32 are slightly curved as indicated at 33 to facilitate the placing of the tongue or shank 31 under the sleeve 4 carried by the bolt 27 as 45 will be obvious in considering Figures 2 and 5 of the drawings.

From the foregoing description it will be 50 seen that a very simple and efficient device has been produced in the nature of a valve spring compressor which may be very conveniently and easily operated. Simply by adjusting the abutment shoe 7 in the desired 55 position upon the rails 3 and placing the spring so that one end thereof will engage the abutment shoe 7 and the other end engage the compression shoe 18, the lever 21 may be drawn inwardly or toward the operator, 60 thereby fully compressing the spring at which

time the usual clip may be attached thereto or should the clip known as the "Wainwright" clip fully set forth in the above identified Patent 1,614,218, be used, the clip of course may be attached at the first instance 70 to the spring and by compressing the same the clip will automatically and progressively engage the convolutions of the spring thereby automatically attaching the clip to the 75 spring. This invention, of course, has particular reference to the compressor itself and not to the particular type of clip used in view of the fact that this device has been particularly designed to accommodate itself to the use of any particular clip desired in 80 conjunction with the spring to be compressed.

It should be further borne in mind that by producing a tool as described and illustrated, from round edge cold rolled steel or 85 similar standard or stock material the cost of producing a very efficient as well as a sturdy tool has been reduced to the minimum.

It should be understood that certain detail changes in the mechanical construction may 90 be employed without departing from the spirit of the invention, so long as these changes fall within the scope of the appended claims.

What is claimed is:

1. A valve spring compressor comprising a pair of parallel tracks, means for supporting said tracks in spaced relation, brackets for supporting the ends of said track, a compression shoe slidably mounted upon said tracks, an abutment shoe anchored upon said track, each of said shoes comprising an upper and a lower plate having overhanging flanges engaging said tracks and means passing through the plates for binding the same together upon said tracks, an operating lever carried by said compression shoe, a link connected to one end of said operating lever, a bracket carried by said tracks and pivotally supporting the opposite end of said link, and spring engaging means carried by each of 100 said shoes.

2. A valve spring compressor comprising a pair of parallel tracks, an abutment shoe adapted to be anchored in an adjusted position upon said tracks, a compression shoe slidably mounted thereon, means for actuating said compression shoe, means for spacing said tracks, supporting brackets carried by the ends of said tracks, means passing 105 through said tracks and spacing means for holding the tracks together, and said brackets provided with overhanging bifurcated ends fitting snugly over the top edges of the tracks for firmly locking the same in an anchored position.

3. A valve spring compressor comprising a trackway, a shoe mounted upon said trackway, compression means associated with said shoe, said shoe comprising a pair of opposite- 110

50 by arranged plates overhanging said trackway, a locking bolt passing through said plates for locking the same in engagement with said trackway, a wing nut carried by said bolt, a wrench fitting over said bolt and provided with a downwardly bent bifurcated end adapted to straddle the wing of said wing nut to facilitate the tightening of said wing nut upon said bolt.

55 4. A valve spring compressor comprising a trackway, a shoe mounted upon said trackway, compression means associated therewith, said shoe comprising an upper plate, means for locking the same upon said trackway, a spring engaging finger anchored to the under face of said plate and extending upwardly at right angles thereto and adapted to engage one end of a valve spring while the same is being compressed or removed from a supporting clip, and a valve spring 60 engaging means carried by said compression means.

65 5. A valve spring compressor comprising a trackway, a compression shoe slidably mounted upon said trackway, an operating lever pivotally mounted upon said compression shoe, a link engaging one end of said lever, a supporting strap secured to said trackway and provided with a laterally extending end constituting a pivot support for said link, said strap passing down under said trackway and means passing through said strap for anchoring the same to said trackway.

70 35 6. A valve spring compressor comprising a trackway, an abutment member carried by said trackway, a removable abutment plate having a disc shaped end fitting against said abutment, means engaging the track for holding said abutment plate in position thereon, and compression means associated therewith.

75 40 7. A valve spring compressor comprising a trackway consisting of a plurality of side rails, an abutment member mounted upon said trackway, an abutment plate comprising an upwardly extending disc-like member, and a forwardly extending rib fitted between said track rails for removably supporting said abutment plate in engagement with said track rails, and compression means associated therewith.

80 55 8. A valve spring compressor comprising a pair of track rails, means supporting the ends thereof, a centrally located transverse bracing member extending between said track rails, a strap extending under said track rails, said strap being bent upwardly and having a laterally extending end, a link supported thereby, a compression member slidably mounted upon said track rails, an operating lever carried by said compression member and engaging said link, an abutment member, an abutment plate removably engaging said abutment member, and provided with an upwardly extending disc-like portion, and

85 a forwardly extending tongue fitting between said track rails and under said centrally located bracing member for removably supporting said abutment plate in engagement with said track rails.

90 50 9. A valve spring compressor comprising a track, an abutment shoe mounted upon said track, a compression shoe slidably mounted upon said track, an operating lever pivotally connected intermediate its ends to said compression shoe and extending across said track, a link for pivotally supporting the inner end of said lever, and means for anchoring said link upon said track whereby the swinging of said lever will slide said compression shoe toward or away from said abutment shoe.

95 55 10. A valve spring compressor comprising a track, an abutment member carried by said track, a removable abutment plate fitting against said abutments, means engaging said track for holding said abutment plates in a position thereon, and compression means associated therewith.

100 60 In testimony whereof I affix my signature.

JOSEPH E. WAINWRIGHT.
